CORPORATION OF MASSACHUSETTS.

MISTTHREADING DEVICE FOR AUTOMATIC LOOMS.

1,186,756.

Specification of Letters Patent. Patented June 13, 1916.

Application filed December 15, 1913. Serial No. 806,784.

To all whom it may concern:

Be it known that we, CLARE H. DRAPER and JONAS NORTHRUP, citizens of the United States, residing at Hopedale, in the 5 county of Worcester and State of Massachusetts, respectively, have invented certain new and useful Improvements in Mistthreading Devices for Automatic Looms; and we do hereby declare the following to 10 be a full, clear, and exact description of the invention, such as will enable others skilled in the art to which it appertains to make and use the same.

The present invention relates to an improvement in mistthreading devices for automatic looms.

In automatic looms the breaking of the filling when a new filling supply is inserted in the shuttle, called a "hopper mistread," 20 causes a filling absence to be detected upon the next boxing of the shuttle on the detector side of the loom, and the insertion of a new filling supply upon the next boxing 25 of the shuttle on the filling supply side of the loom.

Two hopper mistreads in plain weaving will not result in a conspicuous defect in the cloth, and one object of this invention is to produce a construction operating upon 30 three consecutive hopper mistreads to stop the loom.

Sometimes when a new filling supply is inserted in the shuttle the thread will fail to enter the shuttle eye, that is, a so-called 35 "real mistread" occurs, and on the first stroke of the shuttle across the loom a filling will be laid in the shed, and filling presence indicated at the filling detector. Upon the next stroke of the shuttle this 40 thread will break, and on the next stroke thereafter a filling absence will be indicated which may be availed of either to cause the insertion of a new filling supply in the shuttle or to stop the loom. Inasmuch as 45 one real mistread leaves only two filling absences in the cloth, it is not necessary to stop the loom on a single mistread, but upon a second consecutive real mistread, it is desirable to stop the loom because such 50 second consecutive real mistread may indicate that the thread eye of the shuttle is

clogged and the attention of the operative should be directed thereto.

So another object of the invention is to produce a contrivance operating to stop the 55 loom upon the occurrence of two real mistreads.

Other objects of the invention will be pointed out in connection with the description 60 of the machine.

In the accompanying drawings illustrating the preferred form of the invention, Figure 1 is a section on the line 1—1, Fig. 2; Fig. 2 is a plan of a portion of the left-hand end of a loom embodying the invention; Fig. 3 illustrates the mode of operation of the mistthreading device upon the occurrence of three hopper mistreads, position 1 showing the position of the parts upon the indication of filling absence, position 2 showing the position of the parts upon the occurrence of a hopper mistread incident to filling replenishment brought about by the filling absence indicated in position 1, position 3 showing the position 65 of the parts upon the occurrence of a second hopper mistread, and position 4 showing the position of the parts upon the occurrence of the third hopper mistread; Fig. 4 illustrates the mode of operation of the device upon the occurrence of two real mistreads, position 1 indicating filling absence, position 2 indicating filling presence after a real mistread incident to filling replenishment, position 3 indicating filling 70 absence following the breaking of the thread on the return stroke of the shuttle, position 4 indicating filling presence due to the second operation of the filling supply, and position 5 indicating filling absence following the breaking of the thread upon the return stroke after the second filling 75 replenishment; and Fig. 5 illustrates the mode of operation of the device in normal operation of the machine, position 1 indicating filling absence, and the successive positions 80 2 to 6 inclusive indicating the steps by which the mistthreading device is restored to normal position.

The left-hand end of the breast beam 10 100 is slotted to receive the shipper lever 11 and supports the knock-off lever 12. The

weft fork 13 is of the ordinary form, being pivotally supported upon the detector slide 14 mounted in the detector bracket 15 secured to the breast beam in the usual manner. The weft hammer 16 is oscillated in the usual way, and is adapted to engage the hook 17 of the fork to cause the detector slide 14 to be pushed forward so as to set the filling supply mechanism in operation 10 in the usual way through the medium of the rock shaft 20 which extends from side to side across the front of the loom. The detector slide arm 21 mounted on the rock shaft 20 is provided upon its upper end with a link 22 by which the arm 21 is connected to the detector slide 14, the front end of the slide being provided with a recess which receives a boss on the rear end of the link 22. This mode of connecting the detector 20 with the rock shaft running to the filling supply mechanism affords provision for disconnecting the detector from the filling supply mechanism, when desired, by simply unhooking the link 22 from the recess in 25 the end of the detector, which is accomplished by lifting the detector slide 14 so as to permit the link 22 to be disengaged from the recess 23. The front end of the link 22 is hook shaped, as seen in dotted 30 lines in Fig. 1, and hooked over the head 24 of the pin 25. The snout 26 on the upper end of the detector arm 21 normally holds the link 22 from displacement. The above described arrangement is such that 35 upon the indication of filling absence the weft hammer, catching the hook 17 on the fork, moves the detector slide 14 forwardly and thereby causes the detector arm 21 to turn the rock shaft 20 so as to cause the 40 filling supply mechanism to be set in operation.

The mistreading device consists of the contrivance for determining the number of times which the filling supply mechanism shall operate and the conditions under which the stopping of the loom shall be caused. Pivottally mounted on the pin 25 is a knock-off pawl 30 which is moved forward and back by the movements of the detector arm 50 21. This pawl bears upon its side a projection or dog 31 which in Fig. 1 is shown as in engagement with the end 32 of the knock-off lever 12.

By reference to Fig. 2 it will be seen that 55 the parts have operated to cause the pawl to swing the knock-off lever so as to stop the loom. The free or rear end of the knock-off pawl 30 rests upon a knock-off cam 33 which is secured to the side of a ratchet 60 wheel 34. Both are pivoted upon the stud 35 which is supported in the bracket 15. The end of a spring 36 which is secured under the head of the bolt 18 engages the ratchet 34 and operates to complete the forward movements of the ratchet and to pre-

vent backward rotation thereof. The weft hammer is provided with a pawl 37 pivoted at 40 to a projection on the side of the hammer and normally held in elevated position by a spring 41, its tail taking against the stop pin 42. The knock-off cam 33, as shown in Fig. 1, occupies a position in which it has lowered the knock-off pawl sufficiently so that the dog or projection 31 has engaged and operated the stop lever 12 to knock off 75 the loom.

By reference to Fig. 3, the *modus operandi* of stopping the loom upon the occurrence of three successive hopper mistreads is illustrated. In position 1 the knock-off cam 33 80 is shown in the position which it normally occupies. At this time it will be observed that the ratchet wheel 34 presents its toothless surface 43 to the weft hammer pawl 37, so oscillations of the weft hammer, when the 85 ratchet and its attached cam occupy the positions illustrated in this figure, have no effect upon the cam and the ratchet because the pawl 37 does not engage the ratchet wheel 34. But now a filling absence has 90 been indicated and the fork 13 occupies detecting position. The weft hammer has engaged the hook 17 on the fork and has moved the slide forwardly far enough so that the end of the knock-off pawl 30 has 95 dropped into the recess 44 in the knock-off cam 33. Upon the backward movement of the detector arm the knock-off pawl 30 will turn the ratchet 34 and attached cam 33 far enough to bring the next tooth of the ratchet 100 under the end of the spring which thereupon completes the movement of the cam to substantially the position indicated in position 2. The filling absence indicated in position 1 will have done two things, to wit, 105 first it will have set the filling supply mechanism in operation and upon the back stroke of the detector arm 21 it will have caused the knock-off cam 33 to be turned by the engagement of the knock-off pawl 30 with the 110 notch 44 thereof. This one-sixth turn given the knock-off ratchet, which was begun by the pawl and completed by the spring, will bring the tooth 45 of the ratchet into position to be engaged by the pawl 37 on the 115 weft hammer. Now assuming that upon the operation of the filling supply mechanism caused by the filling absence indicated in position 1, the thread from the filling supply is broken at the time the filling supply 120 was inserted in the shuttle, that is, that there was a hopper mistread, then filling absence will be indicated by the fork, as shown in position 2, Fig. 3, and the detector slide will be operated to cause the filling 125 supply mechanism to insert a new filling supply. At the same time the tooth 45 on the knock-off ratchet will be engaged by the pawl 37 on the weft hammer and the ratchet will be turned by the pawl and the spring 130

through another sixth of revolution, bringing the ratchet to the position indicated in position 3. Assuming a second hopper misthread at this time, a third operation of the filling supply mechanism will be produced, the tooth 45 of the ratchet will be engaged by the pawl on the weft hammer, another filling supply will be introduced in the shuttle, and the ratchet 34 will be turned through another sixth of a revolution to the position indicated in position 4 of Fig. 3. Assuming a third successive hopper misthread, the fork will indicate filling absence, the filling supply mechanism will be set in operation, the pawl on the weft hammer will engage the tooth 47 on the ratchet wheel 34 and the ratchet will be turned another sixth of a revolution. This will bring the low side of the cam 33 under the end of the knock-off pawl 30, and the projection or dog 31 will engage the arm 32 of the knock-off lever, as shown in position 4 of Fig. 3, and cause the loom to be stopped by knocking it off.

Referring to Fig. 4, the *modus operandi* of the parts in the event of two real mistreads, will be readily understood. In position 1 filling absence has been indicated and the ratchet set in motion by engagement of the knock-off pawl with the knock-off cam. In position 2 filling presence is indicated, but the tooth 45 of the ratchet is engaged by the pawl on the weft hammer and the step by step advance of the ratchet and the knock-off cam is continued. In position 3 filling absence is indicated owing to the breaking of the thread on the back stroke of the shuttle and the second operation of the filling supply mechanism is produced. Assuming that another real mistread occurs, the parts occupy the positions indicated in position 4; filling presence being indicated, but the racking of the knock-off cam has been continued, and if filling absence occurs upon the next detecting stroke, the loom will be stopped owing to the parts occupying the positions indicated in position 5.

In Fig. 5 the successive positions of ratchet and cam are shown, where a filling absence is detected, filling supply provided and normal operation of the loom ensues. In all of the positions after the first the fork is lifted by filling presence and the detector slide is not carried forward by the weft hammer at the time the low part of the cam 33 is under the end of the knock-off pawl 30, as in either of positions 4 or 5, so the loom continues uninterruptedly in weaving operation. It is true of course that should a filling breakage occur during positions 4 or 5 there would be a loom stoppage. But inasmuch as filling breakage other than a hopper mistread or a real mistread is of rare occurrence, the effect of loom stoppage

brought about in this way upon the production of cloth will be negligible.

It is to be observed that this construction affords provision for knocking off the loom upon the occurrence of three successive hopper mistreads or two real mistreads, or two hopper mistreads and one real mistread, or on the successive occurrence of one hopper mistread and one real mistread, or one real mistread and one hopper mistread, as will be readily understood from consideration of the foregoing description of the mode of operation of the device. The loom will continue attempting to restore itself to a condition of normal operation for the number of picks corresponding to those required for three hopper mistreads or two real mistreads or four successive boxings of the shuttle in the filling supply end of the lay.

The invention is not limited to the illustrated embodiment thereof, but it may be embodied in other forms within the scope of the following claims.

Having thus described a specific embodiment of the invention, what is claimed is:

1. An automatic loom, having, in combination, filling supply operating means, a filling detector, means connected with a reciprocating part of the loom, rotary means set in motion thereby, and means controlled by this latter means for causing loom stoppage on the occurrence of three successive hopper mistreads.

2. An automatic loom, having, in combination, filling supply operating means, a filling detector, means connected with a reciprocating part of the loom, means set in motion thereby, and means controlled by this latter means for causing loom stoppage on the occurrence of two real mistreads.

3. An automatic loom, having, in combination, filling supply operating means, a filling detector, means connected with a reciprocating part of the loom, means set in motion thereby, and means controlled by this latter means for causing loom stoppage on the occurrence of a hopper mistread and a real mistread.

4. An automatic loom, having, in combination, filling supply operating means, a filling detector, means connected with a reciprocating part of the loom, means set in motion thereby, and means controlled by this latter means for causing loom stoppage on the occurrence of a real mistread immediately followed by a hopper mistread.

5. An automatic loom having, in combination, filling supply operating mechanism, a filling detector, a weft hammer, a stop-delaying device actuated thereby, and a gravity knock-off pawl for causing loom stoppage adapted to be brought into operative connection with and to be controlled by the stop-delaying device.

6. An automatic loom having, in combination, filling supply operating means, a filling detector, a ratchet and pawl contrivance started by the operation of the filling supply operating mechanism and thereafter continued in operation by a reciprocating part of the loom until it has completed a full revolution, it being constructed and arranged to stop the loom if the filling supply mechanism does not within four attempts properly supply filling to the shuttle. 55
7. An automatic loom having, in combination, filling supply operating means, a filling detector, stopping means, a stop delaying device having provision for being started by the operation of the filling supply operating means and thereafter actuated by the loom, said device having provision for connecting the filling supply operating means with the stopping means to stop the loom. 60
8. An automatic loom having, in combination, filling supply operating means, a filling detector, connections between the detector and the filling supply operating means, stopping means, connections between the filling supply operating means and the stopping means including a normally inoperative part, means connected with the filling supply operating means for setting such inoperative part in operation, actuating means for such part, said part having provision for controlling the stopping of the loom by the filling supply operating means. 65
9. An automatic loom having, in combination, filling supply operating means, a filling detector, stopping means, a rotary stop delaying device and means for actuating the stop delaying device, the device having provision by virtue of which, when it is in motion, it makes a complete rotation before again regaining an inoperative position. 70
10. An automatic loom having, in combination, filling supply operating means, a filling detector, stopping means, and a pawl and ratchet stop delaying device consisting of a ratchet and toothed cam, the stopping means being controlled by the pawl and ratchet stop delaying device. 75
11. An automatic loom having, in combination, filling supply operating means, a filling detector, stopping means, and a rotary stop delaying device having provision for actuation by the filling supply operating means and by a reciprocating part of the loom. 80
12. An automatic loom having, in combination, filling supply operating means, a filling detector, means for causing loom stoppage having a delaying device for delaying the stoppage of the loom, and a spring and pawl device mounted on the weft hammer for actuating the delaying device. 85
13. An automatic loom having, in combination, filling supply operating means, a filling detector, and means for causing loom stoppage constructed and arranged to stop the loom when filling is absent on a detecting beat following filling supply replenishment, present on the next detecting beat, and absent on the next detecting beat. 90
14. An automatic loom having, in combination, filling supply operating means, a filling detector, a ratchet and pawl contrivance started by the operation of the filling supply operating mechanism constructed and arranged to stop the loom if the filling supply mechanism does not within three attempts properly supply filling to the shuttle. 95
15. A loom, having in combination, filling detector mechanism, filling supply controlling means adapted to be actuated when filling is absent on a detecting beat, and means controlled in its operation by the filling detector mechanism for causing loom stoppage whenever filling is absent on two successive detecting beats causing replenishment, present on the next detecting beat, and absent on the next detecting beat. 100
16. A loom, having in combination, filling detector mechanism, filling supply controlling means adapted to be actuated when filling is absent on a detecting beat, and means controlled in its operation by the filling detector mechanism for causing loom stoppage whenever filling is absent on three successive detecting beats causing replenishment, present on the next detecting beat, and absent on the next detecting beat. 105
